United States Patent Office

Des. 204,664
Patented May 10, 1966

204,664

WINDOW FRAME

John J. Halko, Jr., 205 Llangollen Blvd., Llangollen Estates, Del., and Marvin S. Reider, Pottstown, Pa. (½ Small Castings, Inc., R.D. 1, Bechtelsville, Pa.)

Filed Dec. 31, 1963, Ser. No. 77,993

Term of patent 14 years

(Cl. D13—1)

Fig. 1.

Fig. 2.

Fig. 3.

Fig. 4.

Fig. 5

FIG. 1 is a front view of a window frame showing our new design;

FIG. 2 is an enlarged detailed view more fully showing the novel features of the new design;

FIGS. 3 and 4 are detailed views similar to FIG. 2 of slightly modified embodiments of our new design; and

FIG. 5 is a side view of the construction shown in FIG. 2.

The sashes shown in dash line in FIG. 1 are disclosed for illustrative purposes only.

We claim:

The ornamental design for a window frame, as shown and described.
